UNITED STATES PATENT OFFICE.

EDWARD FALES, OF BOSTON, MASSACHUSETTS.

STOVE OR FURNACE.

SPECIFICATION forming part of Letters Patent No. 505,449, dated September 26, 1893.

Application filed January 24, 1893. Serial No. 459,589. (No model.)

To all whom it may concern:

Be it known that I, EDWARD FALES, of Boston, county of Suffolk, State of Massachusetts, have invented an Improvement in Stoves or 5 Furnaces, of which the following description, in connection with the accompanying drawings, is a specification, like letters on the drawings representing like parts.

This invention has for its object to improve 10 the construction of the stove or furnace shown and described in my application for Letters Patent, Serial No. 437,934, filed June 5, 1892, and my invention consists in improvements in the top wall of the fire pot or chamber, 15 whereby the smoke or floating particles may be better or more perfectly consumed.

Figure 1, shows in front elevation and partial section a stove or furnace embodying this 20 invention; Fig. 2, a right hand side elevation 25 and partial section of the stove shown in Fig. 1.

The fire pot or chamber comprising the front wall, rear wall, end walls and top wall, and the series of parallel vertical ribs *c*, formed upon the inner side of said rear wall, 25 presenting guide passages or flues for the flame and products of combustion, and the thin smoke consuming chamber rising from said fire pot directly above the said guide 30 passages or flues, and preferably having a series of small passages communicating with and forming continuations of said guide 35 passages or flues are all substantially as in the aforesaid application.

The top wall *e* of the fire pot has formed 35 upon its under side a series of parallel ribs *e'*, arranged opposite the ribs *c*, the bottoms

or outer edges of said ribs *e* declining toward the rear wall of the fire pot so that the greater height is left for the fire pot or chamber at or near the front wall. By means of these ribs 40 guide passages are formed for directing the flame and products of combustion to the smoke consuming chamber, and as the ribs become very hot, many of the floating particles are burned while passing through said passages. 45 By declining the outer edges of said ribs as best shown in Fig. 2, it will be seen that greater depth is obtained for said passages as they approach the rear wall. I do not however desire to confine my invention to any 50 particular shape or proportions of said ribs *e'*.

I claim—

1. In a stove or furnace, the fire pot or chamber, the top wall *e* of which has a series of parallel arranged ribs *e'*, upon its under side, and 55 the thin smoke consuming chamber rising from the fire pot, substantially as described.

2. In a stove or furnace, the fire pot or chamber, the top wall *e* of which has a series of parallel arranged ribs *e'*, upon its under side, declining toward the rear end, and the thin smoke consuming chamber rising from the 60 fire pot at said rear end, substantially as described.

In testimony whereof I have signed my 65 name to this specification in the presence of two subscribing witnesses.

EDWARD FALES.
